UNITED STATES PATENT OFFICE.

JAMES LEAMON REYNOLDS, OF SCOTTDALE, PENNSYLVANIA.

WEAVING-MACHINE.

1,392,657.

Specification of Letters Patent.

Patented Oct. 4, 1921.

Application filed November 2, 1920. Serial No. 421,245.

To all whom it may concern:

Be it known that I, JAMES LEAMON REYNOLDS, a citizen of the United States, and a resident of Scottdale, in the county of Westmoreland and State of Pennsylvania, have invented certain new and useful Improvements in Weaving-Machines, of which the following is a specification.

The present invention relates in general to weaving machines, and more particularly to a weaving machine especially adapted for making screen fabric from relatively heavy metallic rods.

The object of the invention is to provide a weaving machine of this character which is extremely simple and durable in construction, reliable and efficient in operation and easy and inexpensive to manufacture and maintain and which is capable of effecting the speedy production of a high grade metallic fabric at a minimum cost.

Other objects and advantages of the invention reside in certain novel features of construction, combination and arrangement of parts as will be hereinafter more fully described and particularly pointed out in the appended claims, reference being had to the accompanying drawings forming part of this specification, and in which:

Figure 1 is an elevational view of one side of the machine;

Fig. 2 is a similar view of the opposite side;

Fig. 3 is a fragmentary plan view of the machine;

Fig. 4 is a vertical longitudinal sectional view, on line 4-4 of Fig. 3 and looking in the direction of the arrows;

Fig. 5 is a transverse vertical sectional view, on line 5-5 of Fig. 1 and looking in the direction of the arrows;

Fig. 6 is a detail view of a rock shaft;

Fig. 7 is a detail view of the clamp bar of the feeding mechanism;

Fig. 8 is a detail view of the link pivots;

Fig. 9 is a detail view of the bit of the die;

Fig. 10 is a detail view of the swinging cross head;

Fig. 11 is a detail view of one of the dies;

Fig. 12 is a detail perspective view of one of the rock arms;

Fig. 13 is a detail perspective view of the angle rest for the screen;

Fig. 14 is a detail view of one of the clamp screws; and

Fig. 15 is a detail view of the cross head pivot.

Referring to the drawings it will be seen that the machine includes a frame or bed 60 supported upon suitable legs 11.

A pair of horizontally spaced and aligned journal frames designated at 13 and 14 are arranged upon and suitably secured to the bed 10 at one end thereof. Rock shafts 16 65 and 16^b are mounted for rocking movement in the journal frames 13 and 14 and, as clearly shown in Fig. 4, are vertically spaced and aligned. These rock shafts are of identical construction and as shown in detail in Fig. 6 the body portion 16^b thereof is of polygonal shape or cross section, preferably octagonal. Adjacent each end the shaft is provided with smooth portions 16^c circular in cross section and adapted to be received in the journals of the journal frames for 70 rotational and longitudinal sliding movement. One end of the shaft is provided with an annular groove 16^d and the other end is of polygonal form, as indicated at 16^e for a 80 purpose to be hereinafter more fully described.

A series or plurality of dies, designated at 18, is arranged upon the upper rock shaft 16 and a coacting series of dies designated 85 at 19, is arranged upon the lower rock shaft 16^a. The dies which make up each series are identical in construction and as shown in detail in Fig. 11 consist of a body portion 20 provided with a polygonal shaped opening therethrough conforming to and snugly fitting the polygonal portion 16^b of the rock shaft with which it is associated whereby the dies are constrained to partake of the motion of the shafts. The body portion 20 90 is provided with an outwardly extending die or bit holder 22 which is provided in its outer end with a socket 23 to receive the die proper or bit 24. When the dies of each series are arranged upon their rock shafts the 100 dies proper or bits 23 are maintained in spaced relation by means of the body portions 20 and are secured to the rock shaft by means of collars 25 and set screws or lock pins 25^a.

As shown in the drawings the dies of the series 18 are staggered with respect to the dies of the series 19 that is to say, the dies of the series 18 are opposite the spaces between the dies of the series 19 and the dies of 110 the series 19 are opposite the spaces between the dies of the series 18. The warp rods

which the dies engage and bend are designated at X and there is provided one die for each warp rod. The dies of the upper series 18 engage alternate warp rods from the upper side and the dies of the lower series 19 engage alternate warp rods from the lower side and as the dies of one series are staggered with respect to the dies of the other the warp rods engaged by one series are not engaged by the other and the dies effect opposite bending of adjacent warp rods when they partake of oppositely swinging movement imparted to them by the rock shafts.

15 Means is provided for driving or rocking the rock shafts and the dies of each series in opposite directions and includes a pressure cylinder 27 closed at its ends by cylinder heads 28 and 29, respectively. The pressure cylinder 27 is supported by means of a web 28^a integrally formed with the cylinder head 28 and bolted to the bed 10. A piston 30 is slidably arranged in the pressure cylinder and is provided with a piston rod 31 extending through a suitable stuffing box 32 in the upper head 28 of the cylinder. The piston rod is pivotally connected at its upper end to the lower end of an adjustable pitman 33, as indicated at 34, the upper end of which is pivotally connected, as at 35, to one end of a swinging cross head 36, shown in detail in Fig. 10, which is pivotally mounted by a pivot 37, shown in detail in Fig. 15 and carried by a lug 38 integral with one of the journal frames. A link 39 has one end pivotally connected to the swinging cross head by means of a pin 40, shown in detail in Fig. 8, and has its opposite end pivotally connected, as at 41, to a rock arm 42 fixed to the upper rock shaft 16. A second link 43 is pivotally connected at one end, as at 44, to the swinging cross head and is pivotally connected at its other end, as at 45, to a second rock arm 46 which is fixed to one end of the lower rock shaft 16^a. It is obvious that when pressure, such as steam, air or the like, is admitted to the lower side of the piston it forces the piston upwardly in the cylinder and swings the cross head 36 about its pivot and by the action of the links and rock arms induces opposite rocking motion of the rock shafts 16 and 16^a.

In order to return the piston to its lower position in the cylinder, and to return the rock shafts to their original position the cross head is provided with a counter-weight 50.

To relieve these instrumentalities of jar and shock on the return movement the piston rod 31 is provided with an integral annular collar 31^a at its upper end adapted to engage on its downward movement a coil spring 31^b arranged around the piston rod, as shown in Fig. 5 and thus take up any shock or jar that might occur.

Shifting mechanism is provided for the rock shafts 16 and 16^a and the dies which they carry and consists of a shifting yoke 51 pivoted at 52 to one of the journal frames and having an upper and lower pair of pins, 70 designated at 53 and 54, respectively, which project into the annular groove 16^d on the ends of the rock shafts 16 and 16^a, respectively. At the upper end of the yoke there is provided a cross bolt 55 which is selectively engageable with notches 56 formed in the latch bar 57 which is pivoted at 58 to the top of the journal frame. By means of the latch bar 57 the shifting yoke may be held in desired position.

80 Feeding means is provided for advancing the screen through the machine and consists of a pair of screw shafts 60 and 61 journaled in bearings 62 and 63, respectively, and arranged along each of the longitudinal sides 85 of the bed of the machine. The screw shafts 60 and 61 are driven from a common drive shaft 64 journaled in bearings 65 and driving the screw shafts 60 and 61 by means of gearing 66 and 67, respectively. A carriage 90 68 is arranged upon and adapted to be traversed back and forth by means of the screw shafts. The carriage 68 includes a clamping bed 69 having a contour conforming to the contour of the screen so as to receive and 95 grip the same and a coöperating clamping bar 70 adjusted toward and away from said clamping bed by means of clamp screws 71 shown in detail in Fig. 14. The power shaft 64 which actuates the feeding mechanism 100 105 may receive its power from a motor but is preferably adapted, as at 64^a to be actuated by a hand crank (not shown).

Beyond the carriage 68 the screen is received and rests upon an angle screen rest 105 72 mounted on the bed by means of suitable supporting lugs 73.

In operation when pressure is admitted to act upon the underside of the piston 30, the piston is forced upwardly in the cylinder 110 and the swinging cross head is rotated about its pivot and through the links 39 and 43 and rock arms 42 and 46 effect an oppositely rocking movement of the rock shaft 16 and 17 so as to swing the staggered dies of the 115 series 18 and 19 toward and past each other. The dies of the series 18 engaging every other one of the rods or wires and the dies of the series 19 engaging the alternate warp rods intermediate those engaged by the series 18 bend these rods past each other and about the weft rods which have been previously inserted so as to properly associate the warp rods with these weft rods and to form a shed through which the next weft 125 rod may be inserted. The cylinder 27 is then relieved of pressure so that the counter-weight 40 is effective to return the piston and the rock shafts and the dies which they carry to their original position. The shift- 130

ing mechanism is then actuated to shift the dies of each series so that they again engage the warp rods to repeat the bending operation and after the weft rod has been inserted

5 this cycle of operation may be repeated. With each operation of the dies the feeding means holds the warp rods so that they may be properly bent and with each insertion of a weft rod the feeding mechanism is actuated to advance the screen across the bed to the desired extent. For this purpose, the power shaft 64 is turned and it imparts the desired rotation to the screw shafts 60 and 61 which cause the carriage 68 to which the

10 screen is clamped to traverse the bed and thus advance the screen as desired.

It is to be understood that this machine is most especially adapted for use with slat members or wire members which have been 15 previously crimped.

I claim:

1. In a machine of the character described, a bed, journal frames arranged upon one end of said bed and having upper and lower journals therein, rock shafts arranged in said upper and lower journals respectively for rocking and sliding movement, a series of dies on the upper rock shaft adapted to engage alternate warp rods from the upper side, a series of dies on the lower rock shaft staggered with respect to the dies of the upper series and adapted to engage alternate warp rods from the underside, means for imparting oppositely rocking movement to said rock shafts to swing said dies and the warp rods which they engage toward and past each other, shifting mechanism associated with the rock shafts for repositioning the dies after each bending operation, feeding mechanism adapted to hold the screen during the bending operation and advance the warp rods between the rock shafts before each bending operation.

2. In a machine of the character described, a bed, journal frames arranged upon one end of said bed and having upper and lower journals therein, rock shafts arranged in said upper and lower journals respectively for rocking and sliding movement, a series of dies on the upper rock shaft adapted to engage alternate warp rods from the upper side, a series of dies on the lower rock shaft staggered with respect to the dies of the upper series and adapted to engage alternate warp rods from the underside, shifting mechanism associated with the rock shafts for repositioning the dies after each bending operation, and means for imparting oppositely rocking movement to said rock shafts to swing said dies and the warp rods which they engage toward and past each other.

3. In a machine of the character described, a bed, journal frames arranged upon one end of said bed and having upper and lower journals therein, rock shafts arranged in

said upper and lower journals respectively for rocking and sliding movement, a series of dies on the upper rock shaft adapted to engage alternate warp rods from the upper side, a series of dies on the lower rock shaft 70 staggered with respect to the dies of the upper series and adapted to engage alternate warp rods from the underside, and shifting mechanism associated with the rock shafts for repositioning the dies after each bending 75 operation.

4. In a machine of the character described, rock shafts between which the warp rods are fed, dies on said rock shafts engageable with the warp rods to effect bending thereof, 80 means for imparting rocking movement to said rock shafts, shifting mechanism for repositioning the dies after each bending operation, and feeding mechanism adapted to hold the screen during the bending operation 85 and advance the warp rods between the rock shafts before each bending operation.

5. In a machine of the character described, rock shafts between which the warp rods are fed, dies on said rock shafts engageable with 90 the warp rods to effect bending thereof, means for imparting rocking movement to said rock shafts, and feeding mechanism adapted to hold the screen during the bending operation and advance the warp rods between the rock shafts before each bending operation including a screw shaft, a carriage 95 actuated by said screw shaft, and means for clamping the fabric to the carriage.

6. In a machine of the character described, 100 rock shafts between which the warp rods are fed, dies on said rock shafts engageable with the warp rods to effect bending thereof, means for imparting rocking movement to said rock shafts, feeding mechanism adapted 105 to hold the screen during the bending operation and advance the warp rods between the rock shafts before each bending operation including a screw shaft, a carriage actuated by said screw shaft, and means for clamping 110 the fabric to the carriage including a lead clamping bar having a contour conforming to the contour of the fabric.

7. In a machine of the character described, rock shafts shiftable longitudinally with respect to each other and between which the warp rods are fed, dies on the rock shafts engageable with the warp rods to effect bending thereof and shifting mechanism associated with the rock shafts for repositioning 115 the dies after each bending operation.

8. In a machine of the character described, a bed, journal frames arranged upon one end of said bed and having upper and lower journals therein, rock shafts arranged in said upper and lower journals respectively for rocking and sliding movement, dies on the rock shafts engageable with the warp rods to effect bending thereof 125 and shifting mechanism associated with the 130

4

rock shafts for repositioning the dies after each bending operation, including a shifting yoke fulcrumed to one of said journal frames intermediate the rock shafts and connected on the opposite sides of its fulcrum to the upper and lower shafts respectively.

9. In a machine of the character described, rock shafts between which the warp rods are fed, dies on one of said rock shafts adapted to engage alternate warp rods, dies on the other of said rock shafts staggered with respect to the dies of the first-mentioned rock shaft and adapted to engage alternate warp rods from the opposite side, means for imparting oppositely rocking movement to said rock shafts including a pressure cylinder, a piston therein, a swinging cross head, an adjustable pitman connecting said piston and said cross head, a rock arm fixed to each of said rock shafts, and links connecting said cross head to each of said rock arms.

10. In a machine of the character described, rock shafts between which the warp rods are fed, dies on one of said rock shafts adapted to engage alternate warp rods, dies on the other of said rock shafts staggered with respect to the dies of the first-mentioned rock shaft and adapted to engage alternate warp rods from the opposite side, means for imparting oppositely rocking movement to said rock shafts including a pressure cylinder, a piston therein, a swinging cross head connected to said piston, a rock arm fixed to each of said rock shafts, links connecting said cross head to each of said rock arms, and a counterweight arranged on said cross head for effecting re-

40 turn.

11. In a machine of the character described, upper and lower rock shafts between which the warp rods are fed, a series of dies on the upper rock shaft adapted to engage alternate warp rods from the upper side, a series of dies on the lower rock shaft

50 staggered with respect to the dies of the upper series and adapted to engage alternate warp rods from the under side and means for imparting opposite rocking movement to said rock shafts to swing said dies and the warp rods which they engage toward and past each other including a pressure cylinder, a piston therein, a swinging cross head connected to said pistons, a rock 55 arm fixed to each of said rock shafts, and links connecting said cross head to each of said rock arms.

12. In a machine of the character described, a series of dies adapted to engage every other warp rod from one side, a second series of dies adapted to engage alternate warp rods intermediate those engaged by the first-named series and from the opposite side, said first mentioned series and 65 said last-mentioned series being shiftable transversely with respect to each other, means for imparting oppositely rocking motion to said dies, and shifting mechanism for shifting said series transversely to reposition the dies after each bending operation.

13. In a machine of the character described, rock shafts between which the warp rods are fed, dies on one of said rock shafts adapted to engage alternate warp rods, dies 75 on the other of said rock shafts staggered with respect to the dies of the first-mentioned rock shaft and adapted to engage alternate warp rods from the opposite side, means for imparting oppositely rocking 80 movement to said rock shafts including a pressure cylinder, a piston therein, a swinging cross head connected to said piston, a rock arm fixed to each of said rock shafts, links connecting said cross head to each of 85 said rock arms, a counterweight arranged on said cross head for effecting return, and resilient means associated with said last named means for cushioning the return thereof.

JAMES LEAMON REYNOLDS.
